UNITED STATES PATENT OFFICE.

WILLIAM G. LEE, OF ALLEGHENY, PENNSYLVANIA.

TOY GUN.

No. 862,979.

Specification of Letters Patent.

Patented Aug. 13, 1907.

Application filed August 13, 1906. Serial No. 330,354.

To all whom it may concern:

Be it known that I, WILLIAM G. LEE, a citizen of the United States of America, residing at Allegheny, in the county of Allegheny and State of Pennsylvania, have 5 invented certain new and useful Improvements in Toy Guns, of which the following is a specification, reference being had therein to the accompanying drawing.

This invention relates to certain new and useful improvements in toys, and this invention has for its object to provide a simple, harmless, and inexpensive toy, which will afford considerable amusement to juveniles.

Another object of this invention is to provide a noiseless gun for projecting small pieces of paper card-board 15 and the like, thus providing a toy that can be used in a game where skill is required or simply as an amusement for children.

A further object of this invention is to provide a strong, durable and easily operated toy, free from danger of injury by ordinary use.

With the above and other objects in view which will appear as the invention is better understood, the same consists in the novel construction, combination and arrangement of parts to be hereinafter more fully described, illustrated and then specifically pointed out in the claims.

Referring to the drawing, Figure 1 is a perspective view of my improved toy in position to be discharged, Fig. 2 is a side elevation of the same, partly in section 30 and with the discharge member released, Fig. 3 is a plan of the toy, with the discharge member engaged with the trigger, Fig. 4 is a perspective view of a piece of paper or card board projected by my improved toy.

My improved toy is preferably constructed of wood, 35 but it is obvious that any suitable material may be used. The toy in shape conforms to a pistol or revolver, having a handle 1 and a barrel 2. The rear end of the barrel is slotted, as at 3, and in said slot a trigger 4 is pivoted at 4' and having its upper and lower ends 40 notched, as at 5 and 6. The upper end of the trigger is formed with two surfaces inclined to the longitudinal plane thereof at each side of the notch 5, the inclined surfaces being at unequal distances from the pivot pin 4'. The trigger 4 is formed with a finger grip 6' extending rearwardly of the lower notch 6.

Fastened to the forward end of the barrel 2 is an elastic band or string 7, adapted to lie along the top surface of the barrel and engage in the notch 5 of the trigger 4. To retain the elastic 7 in such a position, I

secure another elastic 8 to the under side of the barrel 50 2 and place the free end of said elastic over the depending end of the trigger, to engage in the notch 6 of said trigger.

The slot 3 is long enough so that the trigger will swing with its upper end rearwardly of the pivot 4' 55 and its forward end forwardly of the pivot when in operative position as shown in Fig. 2, the notch 5 being then disposed close to the upper surface of the barrel, with the upper end of the notch extending rearwardly and thus retaining the elastic member 7, and preventing accidental displacement. By this arrangement when the trigger is actuated the elastic member 7 will be first elevated and carried forward and retained in connection with the notch 5 until the trigger has passed its vertical position and the elastic member 65 has been carried downwardly again relatively close to the barrel, and in position to act with certainty upon the projectile 10. By this means no danger exists of the operating elastic member 7 engaging the projectile above its center but will strike the projectile below its center line with certainty. This is an important feature of the invention and adds materially to its efficiency and utility.

The top of the barrel 2 is provided with a slit 9 in which a piece of paper, card-board or the like material 75 10 is placed, this material forming the shot or projectile of the toy gun.

After the toy gun has been set as above described and a piece of paper is placed in position, the gun is ready to be fired or operated by simply pulling upon 80 the trigger 4. As the elastic 7 is released, the piece of paper 10 is carried forward and projected from the end of the barrel 2 and the elastic 7, said elastic giving the piece of paper sufficient impetus to carry it a considerable distance.

It is apparent from the simple construction of my improved toy, that the elastic thereof can be easily and quickly removed at any desired time, should they break or need renewing.

I do not care to confine myself to the exact shape of 90 the toy as shown or to the projectile used.

Such changes in the details of construction as are permissible by the appended claims, may be resorted to without departing from the spirit and scope of the invention.

What I claim and desire to secure by Letters Patent, is:—

A toy gun comprising a stock and barrel with an aper-

5
tire at the juncture of the stock and barrel and with a socket in the barrel in advance of the aperture, a trigger consisting of a bar pivoted to swing in said aperture and projecting below the barrel and terminating in a finger grip and with a notch at the juncture of the finger grip and the body of the trigger, the upper end of said trigger having a central notch and with the end of the trigger at opposite sides of the end notch inclined to the longitudinal plane of the trigger, an elastic band carried by said barrel

and engaging the notch adjacent to the finger grip, and 10 an elastic band carried by said barrel and adapted to engage the end notch of the trigger.

In testimony whereof I affix my signature in the presence of two witnesses.

WILLIAM G. LEE.
